UNITED STATES PATENT OFFICE.

CARL A. MATSON, OF CHELSEA, MASSACHUSETTS, ASSIGNOR, BY MESNE ASSIGNMENTS, TO SHOE LACE COMPANY, LTD., OF PROVIDENCE, RHODE ISLAND, A CORPORATION OF RHODE ISLAND.

LACE-TIPPING MACHINE.

Application filed September 28, 1923. Serial No. 665,338.

My present invention relates to lace tipping machines, and more particularly to an improved lace tipping machine for simultaneously tipping the ends of a plurality of 5 laces and for measuring the length of such laces.

In my copending application, Ser. No. 474,253, filed June 1, 1921, I have described and claimed an improved process of applying 10 a tip of molded or moldable material to the end or ends of a lacing, such as shoe laces, corset laces, and the like, and my present machine is adapted to more effectively and economically practice the improved 15 method of my copending application than has been heretofore possible.

The machine forming the subject matter 20 of my present invention is to be considered an improvement over other prior machines invented by me and particularly described and claimed in my Patent No. 1,486,838, dated March 11, 1924, and I utilize, in my 25 present machine, the novel idea of the reciprocating or oscillating lace feeding or measuring device described and claimed in my application, Ser. No. 610,142, filed Jan. 2, 1923.

With a view to increasing the output of 30 machines of the class to which the present invention relates, I have designed an improved die comprised essentially of a plurality of separate and distinct heads mounted on a rotating member with means for bringing each of the dies successively into 35 operative relation with respect to the stationary die block. This feature of my invention is believed to be distinctly new and I desire, therefore, to claim the same broadly.

Another feature of my invention is an improved form of chain feed for feeding lacing 40 through the machine and into operative relation with respect to the die block. The successively positioned dies engage a section of lacing about which molded or moldable tipping material is placed and the lacing is 45 severed at a point intermediate the ends of the molded portion, thus separating the indeterminate length of lacings into short lacings of predetermined length.

50 A further feature of my invention relates to an improved device for placing a flat lacing in predetermined position with relation to a die and die block to insure uniformity of product.

A further feature of my invention relates 55 to an improved device in a machine of this character for measuring the length of a lacing to be cut from lacing of indeterminate length. In carrying out this feature of my invention I provide a pair of arms extending 60 rearwardly of the machine and spaced apart from each other, the distance apart being adjustable to suit various lengths of lacings within predetermined limits, and means are 65 associated with such arms for cooperating with the lacing and with the means for throwing said lacing over the ends of the arms.

A still further feature of my invention relates to a device for positively removing the 70 tipped ends of the lacings from the die and die block after the operation of placing the molded or moldable material thereon.

In addition to a device for cutting lacings 75 of predetermined length from a lacing of indeterminate length, I have devised an improved means for cutting from a lacing of indeterminate length extremely long lacings of predetermined length which it would be otherwise impossible to cut with the apparatus 80 above referred to, and in carrying out this function of my invention I have devised a measuring means which brings the lacing over into association with the dies but once in every complete cycle of movement of the 85 lacing feeding means. Also, in carrying out this feature of my invention, the lacing is arranged to be brought into position to be gripped by every alternate member of the chain feeding means, this feature therefore 90 necessitating a readjustment of the rate of feeding of the feeding chains with respect to the rotative speed of the turret head carrying the plurality of dies.

In articles of the present type, it is customary 95 for commercial and practical reasons to count the same in gross lots, the smallest amount referred to in the trade being a gross. It is desirable, therefore, to have means for separating the finished lacings into bundles each containing a gross and I have, therefore, as a further feature 100 of my invention, designed an improved counting means which automatically counts and separates the lacings into bundles or 105 groups each containing a gross.

Various other features of construction and the novel arrangement of parts comprising

my invention will be apparent as the description of the invention progresses.

In the accompanying drawings illustrating the preferred embodiment of my invention,

Fig. 1 is a front elevation;

Fig. 2 is a plan view;

Fig. 3 is a left hand elevation with certain bearings left in for clearness of illustration;

Fig. 4 is a right hand elevation;

Fig. 5 is a vertical central sectional elevation with the die turret shown in elevation;

Fig. 6 is a section on various undefined lines designed to show certain features of construction;

Fig. 7 is a plan on the line 7-7 of Fig. 30;

Fig. 8 is a detail view showing the counting mechanism and the manner of attaching the same to the machine;

Fig. 9 is a section on the line 9-9 of Fig. 8;

Fig. 10 is a sectional detail on the line 10-10 of Fig. 8;

Fig. 11 is an enlarged detail of the counter mechanism operating ratchet on the line 11-11 of Fig. 10;

Figs. 12 to 18 are views of the die and die block, Fig. 12 being a side elevation, Fig. 13 a front elevation, Fig. 14 a rear elevation, Fig. 15 a plan, Fig. 16 a section on the line 16-16 of Fig. 13, Fig. 17 being a section on the line 17-17 of Fig. 13, and Fig. 18 is a section on the line 18-18 of Fig. 17;

Fig. 19 is an enlarged detail showing the chain feeding device;

Fig. 20 is a plan view of Fig. 19;

Fig. 21 is a side elevation of the starting and safety device;

Fig. 22 is a rear elevation of the starting and safety device;

Fig. 23 is a vertical section on the line 23-23 of Fig. 22;

Fig. 24 is a section on the line 24-24 of Fig. 23;

Fig. 25 is a section on the line 25-25 of Fig. 21;

Fig. 26 is a sectional detail on the line 26-26 of Fig. 5;

Fig. 27 is a sectional detail on the line 27-27 of Fig. 3;

Fig. 28 is a sectional detail on the line 28-28 of Fig. 2;

Fig. 29 is a sectional detail on the line 29-29 of Fig. 6, and

Fig. 30 is an elevation of the entire machine.

Referring to the drawings, 10 designates a base or pedestal on an extension 11 of which is mounted a driving motor 12 which, by means of a belt 13, transmits power to a horizontally mounted shaft 14 to which is secured a bevel pinion 15 which meshes with, and drives, a corresponding bevel pinion 16 secured to the lower end of a vertically

mounted shaft 17. Secured to the top of the base or casing 10 is a casing 18 on and on which is mounted the working parts of the apparatus. The shaft 17 extends upwardly through the base 10 and through the casing 18, a bearing member 19 being provided in such casing 18 to support the upper end of the shaft. Secured to the upper end of the shaft 17 is a worm 20 and between the lower end of the worm 20 and the upper end of the bearing 19 is arranged an anti-friction thrust bearing 21. The worm 20 meshes with, and drives, a worm wheel 22 rotatably mounted on the shaft 23 that is, in turn, rotatably mounted in suitable bearings 24 on the casing 18. Secured to one face of the worm wheel 22 in any suitable manner, as by screws 25, is a substantially circular plate 26 to one face of which is secured, in any suitable manner, a plurality of radially disposed dies.

Each of the dies referred to is comprised of a hollow body member 27 having one face thereof provided with a slot or groove 28 and the lower outer end of the member 27 has formed thereon an extension 29 on the top face of which is secured by bolts 30 die plates 31, a pair of these plates being provided and the plates being separated from each other to provide a space or slot 32 therebetween. The upper faces of the die plates 31 are each provided with a groove 33 in alignment with each other and which forms a hook or seat in which the portion of the lacing that is to be tipped is fitted. On the side or end of the member 29 remote from the circular plate 26 and adjacent to the outermost die plate 31 is arranged a slot 34 for a purpose to be hereinafter described. On the outer face of the member 27 is pivotally mounted, by means of a screw 35, a lacing clamp lever 36, one end of which is adapted to move to a position in a plane substantially in the plane in which lies the top surface of the die plate 31 while the other end is provided with an outwardly extending pin 37. Between the pivot screw 35 and the outwardly extending pin 37 on the lacing clamp lever 36 is attached one end of a spring 38, the other end of which is attached to a pin 39 on the member 27. The duplicate of the lacing clamping arrangement just described as being mounted on the outer face of the member 27 is mounted on the face of the plate 26 furthest removed from the described clamping device so that there is, in this manner, arranged a clamping device on each side of the die plate 31 and it will be noted that the springs 38 tend to force the clamping end of the clamping member 36 into position to clamp and engage a length of lacing that may be in position across the face of the die plate 31. Slidably mounted in the interior of the member 27 in a direction toward and from

the die plates 31 is a member 40, the lower forward end of which is cut away to receive a die 41 provided on its under lower surface with a hook-like portion 42 corresponding in contour and size with the curved hook portion 33 in the die plate 31 and with which curved or hook-like portion 33 it is designed to work. A die 41 equal to the width of the pair of die plates 31 may be provided or, preferably, two dies 41 are provided, each substantially equal in width to the width of the die plates 31 and such dies 41 are separated from each other a sufficient distance to allow the insertion between them of a cutter 43, such cutter being held in position in the member 40 by a pin or bolt 44. As will be seen from an inspection of Fig. 17, the cutting edge of the cutter 43 extends forwardly from the groove 42 and the width 20 of such cutter 43 is such as to enable it to be a free sliding fit in the slot 32 formed between the die plates 31 so that, if a lacing is clamped by the clamps 36 across the face of the die plates 31 and the member 40 reciprocated, bringing the die 41 into the position shown in dotted lines in Fig. 16, the cutting edge of the cutter 43 will shear off a length of lacing equal to the width of the slot 32 and thus sever a predetermined 30 length of lacing from a lacing of indeterminate length. What would be termed the upper end of the member 40 is bevelled, as shown at 45, and fitting between this bevelled surface and the upper under surface of 35 the member 27 is a plate 46, the top surface of which is engaged by adjusting screws 47 and by means of which the member 40 is adjusted in the member 27. The rear end of the member 40 is slotted at 48 and such 40 end is also provided with a transverse hole in which fits a shaft 49, which shaft has formed on its outer end an eccentric 50 and on such shaft, in the slot 48, is arranged a roller 51. The outer arm that defines the slot 48 is slotted at 52 and is provided with a bolt or screw 53 which acts as a clamping means for retaining the shaft 49 in fixed relation to the member 40 and thus to maintain the eccentric 50 in any desired position. 50 Secured to one of the bearings 24 is an operating cam 54 which is fixed with relation to the plate 26 and lies in position to engage with the rollers 51 on the shaft 49 on the various die structures. Fixed to the casing 55 18 adjacent the bearing 24, to which is secured the cam 54, is a cam 55 in position to engage with the cams 50 on the end of the shafts 40. Referring now to Fig. 5 showing the plate 26 with the plurality of die structures radially mounted thereon and equally spaced about the circumference of the member 26 and in operative relation to the cams 54 and 55, it will be obvious that the die structure A has the reciprocating member 40 thereof in its rearmost or left-hand posi- 60 tion, as viewed in such figure, by reason of the fact that, assuming the member 26 to be rotating in the direction of the arrow shown, the eccentric 50 will have just come out of engagement with the fixed cam plate 55. In 70 this position of the die structure A, and referring for a moment to either Figs. 12, 16, or 17, it will be noted that the die 41 is in its rearmost position with respect to the die plate 31. As the plate 26 rotates, bringing 75 the die structure A into the next uppermost position, the roller 51 on the shaft 49 will be engaged by the stationary cam 54 and as the roller 51 rides up on the cam surface, the member 40 will be moved radially outward 80 with respect to the center of rotation of the plate 26, bringing the die 41 into its outermost position or into the position shown in dotted lines in Fig. 16. The member 40 is retained in this position until the continued 85 rotation brings the eccentric 50 into engagement with the fixed cam 55 when such cam will move the member 40 and the die 41 carried thereby to its left, or rearmost position, as shown in Figs. 12, 16, and 17. 90

Kotatably mounted in the casing 18 and parallel to each other are shafts 56 and 57 to the outer ends of each of which are secured sprockets 58, the sprockets 58 on each side of the casing 18 being in alignment with each other and over such sprockets run feed chains 59. These feed chains are constructed of a plurality of link members 60 from each of which protrudes a cylindrical member or tooth 61. Side plates 62 connect 100 the links 60 together and the side plates are also provided with extensions 63 substantially equal in length to the length of the cylindrical members 61. Referring to Figs. 17 and 20, and assuming the sprocket 58 to be rotating in the direction of the arrow shown, it will be obvious that, as the chain structure moves in engagement with the sprocket 58, the cylindrical member 61 and the extension 63 on the side plates 62 are 105 separated from each other about the pivot connection of the side plates 62 and links 60 so as to define an angular opening B therebetween, as viewed in side elevation, and into which angular opening it is possible to 110 feed or place a lacing 64 of any length. Assuming now that the cylindrical member 61 and the extension 63 have moved from the position engaged by B so as to bring the chain structure into a substantially horizontal plane, it will be evident that the angular relation of the cylindrical member and extension 63 has disappeared and the lacing 64 that may have been placed in such angular space B will be held or gripped in the 115 manner indicated in Fig. 20. There are two of the feed chains 59, one on each side of the casing 18, and the shafts 56 and 57 rotated at the same speed and in the same direction 120 because of the fact that the sprockets 58 are 125 130.

equal in pitch and diameter. The feed chains 59 therefore move in synchronism and the lacing 64, having been fed to the feed chains, will be moved along by such feed chains in the direction of the constantly rotating turret member 26 on which is mounted the die structures above described. On each side of the member 18 is arranged an adjustable arm 65 at the lower end of which is rotatably mounted an idler sprocket 66 which engages with the lower reach of the feed chains 59 and by means of which the tension of such chains may be adjusted. Secured to the shaft 56 and intermediate the ends thereof is a pinion 67 which meshes with, and is driven by, a gear 68 secured to a shaft 69 rotatably mounted in suitable bearings in the casing 18. Also secured to the shaft 69 is a ratchet 70 which is engaged and driven by a pawl 71 pivotally mounted on an arm 72 rotatably mounted on the shaft 69. To the end of the arm 72 remote from the shaft 69 is pivotally attached one end of a link 73, the other end of which is pivotally attached to one end of a lever 74 rotatably mounted intermediate its ends on a stud 75 secured to one side of the casing 18.

On the shaft 17 and intermediate the ends thereof is secured a worm 76 which meshes with, and drives, a worm wheel 77 secured to a horizontal shaft 78 rotatably mounted in suitable bearings in the casing 18. Secured to the shaft 78 is a cam 79 which engages with a roller 80 rotatably mounted on the lower end of the lever 74 and the cam 79 thus causes an oscillating motion of the lever 74 about its pivot stud 75. Secured to the lever 74 is one end of a spring 81, the other end of this spring being secured at the point 82 to one side of the casing 18 and this spring insures that the roller 80 on the lever 74 is retained in engagement with the face of the cam 79. It will be obvious from the above that, if a cam shaft 78 is rotated in the direction of the arrow shown, an oscillating movement will be imparted to the lever 74, which, through the link 73, imparts an oscillating motion to the lever 72 and thus imparts an intermittent rotary motion to the shaft 69. This intermittent rotary motion to the shaft 69 imparts, through the gear 68 and pinion 67, an intermittent rotary motion to the shaft 56 which, in turn, imparts an intermittent step by step movement to the feed chains 59 from the sprockets toward the constantly rotating die turret.

Secured to the casing 18 between the feed chains 59 and adjacent to the shaft 57 is a tank 83 in which is placed any suitable molded or moldable material, preferably a material capable of being softened under the influence of heat, although dry powdered material may be employed. Rotatably mounted in the casing 18 and extending

through the tank 83 and parallel to the shaft 57 is a shaft 84. Secured to said shaft 84 and lying within the tank 83 is an arm 85 which extends toward the shaft 57. Also secured to the shaft 84, but without the tank 70 75 80 85 90 95 100 105 110 115 120 125 130 135 140 145 150 155 160 165 170 175 180 185 190 195 200 205 210 215 220 225 230 235 240 245 250 255 260 tably mounted on a shaft 108. Pivotally mounted on an arm 109 formed integral with the segmental gear 107 is one end of a connecting rod 110, the other end of which is 5 pivotally mounted to a crank pin 111 secured to, and extending laterally from, one face of a gear 112 secured to a shaft 113 rotatably mounted in the casing 18 and parallel to the shaft 108. The gear 112 meshes with, and 10 is driven by, a gear 114 rotatably mounted on the cam shaft 78. Also secured to the shaft 113 is a gear 115 which meshes with, and is driven by, a gear 116 and rotatably mounted on the cam shaft 78. The gears 15 114 and 116 are spaced apart from each other on the cam shaft 78 and on the cam shaft 78 between the gears 114 and 116 is a clutch member 117. This clutch member is rotatable with, but slidable on, the cam shaft 78 so as to be movable toward either the gear 20 114 or 116 and is provided with a pin 118, the ends of which are adapted to engage with the gears 114 and 116 respectively, this means constituting practically a set of speed 25 change gears for the shaft 105. The member 117 is provided with a circumferential slot in which fits the diametrically opposed pins 119 on the fork 120. This fork is formed on the end of a lever 121 that is 30 pivotally mounted at 122 to the casing 18 and extends outwardly therefrom, as shown in Fig. 2. To the lever 121 adjacent the outer end thereof is pivotally attached one end of a connecting rod 123 which extends 35 rearwardly of the machine to any convenient distance and to a standard 124 is separately mounted on any base or flooring, as shown in Fig. 30. The standard 124, near its top end, has pivotally mounted on a shaft 125 a control lever 126 in which is pivoted the other 40 end of the connecting rod 123. The side of the standard 124, near its top end, is provided with a plurality of perforations 128, 129, and 130 respectively, in any of which is 45 adapted to fit a spring compressed locking member 131 mounted for transverse movement in the lever 126. When the pin 131 is in engagement with the depression 129, the operating lever 126 is in its neutral position 50 and the pin 118 in the member 117 is in engagement with neither of the gears 114 or 116. When the operating lever 126 is pulled to the left, as viewed in Fig. 21, and the pin 131 brought into registry with the depression 55 128, the pin 118 is moved into engagement with the gear 116 and a relatively slow oscillating movement is imparted to the shaft 105 in the manner above described. When the operating lever 126 is moved to the 60 right, as shown in Fig. 21, to bring the pin 131 into registry with the depression 130, the pin 118 is moved into engagement with the gear 114 and a relatively high speed is imparted to the oscillating shaft 105.

65 Secured to the end of the shaft 105 is a

member 132 which is provided with a plurality of transverse perforations through which are slidably mounted arms 133 and 134 respectively, joined together at various points 135 along their length and the outer 70 end of the arm 134 is formed at an angle with the main portion and is provided with a funnel 136 through which may be led the lacing 64.

Connecting the base 10 and the standard 75 124 is a tubular member 136 and mounted on the member 137 extending upwardly therefrom is a member 137 at the upper end of which is provided a hardened bushing 138 and through which passes the lacing 64. 80 Formed integral with the upper end of the member 137 and extending rearwardly therefrom is an arm 139 at the rearward end of which is provided a hardened bushing 140 in alignment with the bushing 138 and through 85 which also passes the lacing 64. Pivotally mounted on the member 137 is a curved member 141, the outer or free end of which is hook-shaped, as shown at 42, and which engages the lacing 64 between the bushings 90 138 and 140, as clearly shown in Fig. 23. Rotatably mounted in the member 137 and the arm 139 and extending therebetween in a plane substantially parallel to the plane in which lies the lacing 64, is a shaft 143, 95 this shaft having secured at one end adjacent the bushing 138 a cutter 144 and intermediate its ends a latch member 145. The latch member 145 is normally, when the device is in operative position, engaged by 100 a latch member 146 rotatably mounted on a shaft or pin 147 in the arm 139. In engagement with the latch member is one end of a trip 148 pivotally mounted at 149 to the end of the arm 139 and on this trip member 105 and intermediate the ends thereof is rotatably mounted a roller 150, the pivot pin 151 for such roller 150 having attached thereto one end of a spring 152, the other end of 110 which is attached at 153 to the arm 139. Lying between the end of the arm 139 and the latch 145 and on the shaft 143 is a spring 154, one end of which is secured to the shaft 143 and the other end of which is secured to the arm 139, this spring being so tensioned 115 as to impart a rotary movement to the shaft 143 and all parts carried thereby, in the direction of the arrow shown in Fig. 24, or in such a direction as to cause the cutting edge of the cutter 144 to sweep across the perforation in the bushing 138. The mechanism just described constitutes a safety device for a lace tipping machine and insures that, if a defect occurs in the lacing 120 passing through the bushings 140 and 138 toward the machine such, for example, as a knot, which is the most prevalent cause of trouble, such knot, engaging with the roller 150, lifts the same against the tension of the 125 spring 152, lifting, in this manner, the end 130

of the lever 148 which, in turn, lifts the latch 146 from engagement with the arm 145 whereupon the spring 154 acts to rotate the shaft 143 and the cutter 144 severs the lacing 64 at the bushing 138. The lacing 64 is led through the bushing 140 from a source of supply, as 155, which lacing is led up through an open ring 156 adjustably mounted for height on a vertically arranged staff 157 secured to the standard 124.

Attached to the standard 124 in any suitable manner, as by screws 158, is a control panel 159 on which are mounted suitable switches 160, fuses, 161, and indicating lights 162 for the driving motor 12. The manner of connecting such controlling and indicating devices to the motor, however, form no part of the present invention and need not be described in detail. Extending laterally from each side of the casing 18 to any convenient distance are parallelly arranged shafts 163 secured together at their outer ends by bars 164 and extending entirely through the casing 18 and rotatably mounted in the bars 164 is a threaded shaft 165 provided with right and left hand threads. Attached to one end of the shaft 165 is an operating handle 166 and by means of which the shaft 165 may be rotated. Slidably mounted on the bars 163 are members 167 the ends of which are internally threaded and through which extends the threaded shaft 165. Referring to Fig. 1 and assuming the threads on the right hand end of the threaded shaft 165 to be right hand threads and the threads on the left hand end to be left hand threads, it is obvious that rotation of the crank 166 in a right hand direction, or in a clockwise direction, will cause the members 167 to move outwardly from the casing 18 toward the bars 164 and the rotation in the opposite direction will cause the members 167 to move inward toward the casing 18. Each of the members 167 is provided with a forked member 168 which surrounds or encloses a bar 169 which extends outwardly from either side of the casing 18 and each forked member 168 is provided with an adjusting screw 170 and with a handle 171. After the threaded shaft 165 has been rotated to adjust the members 167 to their proper or desired position, the adjusting screw 170 is turned by means of the handle 171 to clamp the forked member 168 firmly about the bar 169 and hold the members 167 in adjusted position. To the upper shaft 23 is mounted for sliding movement thereon a hub 172 provided at one end with a circumferential groove 173 in which fits a forked member 174 secured to the upper end of the member 167 by screws 175, the hub 172 being splined on the shaft 23 so as to be capable of sliding movement with respect thereof, but incapable of rotary move-

ment thereon. Secured to the end of the hub 172 remote from the circumferential slot 173 is a circular member 176 provided on its periphery with projections 177 equally spaced about the periphery of the member 176 and equal in number to the number of dies on the plate 26. Referring to Fig. 3, it will be noted that each of the projections 177 is slightly in advance of the die members 40. Formed integral with the members 167 and extending forwardly and upwardly therefrom around the major portion of the periphery of the circular plate 176 and then slightly downwardly and rearwardly to a point adjacent to the vertical plane in which lies the member 132 is a curved horn 178, to the outer rear end of each of which is attached a curved member 179.

Secured to the front of the base 10 by bolts 180 and extending outside of the outer periphery of the major portion of the curved member 178 and then rearwardly and upwardly to a point substantially over the rear end of the member 178 is a member 181 provided on its extreme front lower face with a hook 182 in which may be collected the extremely long lacings tipped by the machine. Intermediate the ends of the member 181 is a boss 183 in which fits the upper end of a supporting shaft or rod 184 and to the lower end of the shaft 184 is attached the forward end of an oven 185 which encloses the impregnated portion of the lacing that lies between the feed chains 59. This oven is provided at its rear end with a handle 188 by means of which it may be placed in position on a device or removed from the device at will. Rotatably mounted on the extreme rearward end of the member 181 is a guide member 189 which may be placed either in the position shown in Fig. 3 or in the position shown in Fig. 1, the spring 187 attached one end to the member 186 and the other end to the member 181 retaining said member 186 in any position in which it may be placed. Mounted on the shaft 57 adjacent and outside of each of the sprockets 53 and extending upwardly and rearwardly therefrom is an arm 189 which, as will be apparent from an inspection of Fig. 5, is located so as to guide a length of lacing extending between the feed chains 59 into the V-shaped space defined by associated cylindrical pins 61 and extension 63 of the feed chain.

In order to insure that the lacing 64 of indeterminate length shall be fed to the die plate 31 in the best possible position, I arrange on the casing 18 between the feed chains 59 longitudinally arranged plates 190 spaced apart from, and extending beneath, the sides of the oven 185 to, in this manner, define with the oven grooves or slots that will insure the lacing 64 which,

at the present day is usually in the form of a flat hollow braid, feeding to the die plate 31 in an edgewise position, as clearly shown in Fig. 26.

5 As the lacings are fed through the die, the lacing of predetermined length is cut off therefrom, as above described, and as the circular plate 176 rotates in unison with the die turret 26, the length of lacing now 10 tipped is engaged by one of the projections 177 on each of the circular plates 176 and carried along in the direction of the arrow shown in, for example, Fig. 4. This lacing will be carried along by the die plate 31 15 and die 40 until the die has its roller 51 engaged by the cam plate 55, which cam plate operates to separate the die 40 from the die plate 31. The die in its onward movement has the pins 37 thereon engaged 20 by the cam member 191 secured to the casting 18. The manner in which this cam 191 operates to rotate the lacing cam levers 86 will be apparent from an inspection of Fig. 3. The severed lacing 64, having now been 25 released from the die mechanism, falls of its own weight and is caught in a bight on the hook 192 secured to a shaft 193 and, in order to insure that no lacings are carried indefinitely around all the projections 177 30 on the circular member 176, means 194 is provided that positively engages any lacing that may be associated with the projections 177.

Pivotaly mounted on a boss 196 formed 35 on the lower inner face of the member 182 is a finger 197 which lies in the path of movement of the various slots 34 between one of the die plates 31 and the member 29, the depth and shape of this slot being indicated by the dotted line in Fig. 12. It will 40 be apparent, therefore, if no lacing 64 lies across the die plate 31, that the normal position of the finger 197, as shown in Fig. 8, will not be disturbed. Further, it will be 45 obvious, if a lacing 64 does lie across the die plates 31, that, as the die structure rotates on its axis, the finger 197 cannot move into the slot 34, being prevented from doing so by the presence of the lacing 64 across the 50 entrance end of the slot and the finger 197 under these circumstances will be moved in the direction of the arrow shown in Fig. 8. Pivotaly attached to the finger 197 intermediate the ends of such finger is one end 55 of a combined pawl and connecting rod 198 pivotaly attached to its other end to the outer end of a link 199 that is pivotaly attached to a shaft 200 secured to the member 181. Rotatably mounted on the pivot point between the members 198 and 199 is a pawl 201, the tooth of which is normally held into engagement with one or the other 60 of the teeth 202 on the ratchet wheel 203 that is rotatably mounted on the shaft 200, such pawl being held in engagement with 65 the teeth 202 by means of the spring 204. The wheel 203 is provided with a total of one hundred and forty four teeth 202 on its periphery so that one complete revolution of the wheel 203 will be necessary to 70 count off one hundred and forty four lacings. Secured to one arm of the wheel 203 by screws 205 is a cam 206 which moves in a path that is normally occupied by a cam member 207 secured to one arm of a bell 75 crank lever 208 rotatably mounted at 209 on a standard 210 formed integral with the member 181. Rotatably mounted on a shaft 211 secured to an arm 212 formed integral with the member 181 is a Geneva 80 movement cam 213 provided, in the present instance, with four operating faces 214 in each of which is the usual groove or depression 215. These grooves 215 are adapted 85 to be engaged by the pin 37 extending laterally from the die structure and rotates the member 213 through a quarter of a revolution. In the normal operation of the device, or when the device is operating on ordinary length lacings, there is a 90 length of lacing extending between opposite pins and extensions 61 and 63 respectively on each of the feed chains 59, but when operating on extremely long lacings, 95 only the opposite ones of every other pin 61 and link 63 are engaged. In operating the counting mechanism, therefore, it is necessary to prevent the ratchet 201 from operating every alternate stroke. To effect this, 100 I arranged members 216 to be inserted in opposite grooves 215 which will build up the outer cam surface of the Geneva movement cam 213 a sufficient extent to cause the pawl 201 to be rotated about its axis so as to be kept out of engagement with the ratchet teeth 203. By this means, only every other stroke of the ratchet 201 becomes effective. On a complete revolution of the ratchet wheel 203, the cam surface 206 engaging with the cam surface 207 rotates 105 the bell crank lever 208 about its axis 209 and moves the hub 217 inward, as viewed in Fig. 8, causing the arm 218 carried thereby to move into the path of one of the pins 37 which thereupon rotates said arm 218 about its axis 219 and grasping the counted bundle of lacings between the member 218 and the member 194. The next 110 lacing coming down will now be brought under the end of the member 218 instead of above, as was the case heretofore, and the lacings will continue to be fed into and below the member 218 until the operator removes the counted bundle from the machine, after which she swings the beginning 115 of the second bundle above the end of the member 218. For lacings of ordinary length, the end 120 of the lacing of indeterminate length is fed 125 through the open eye 156 from the source 130

of supply 155, thence through the bushings 140 and 138 and the funnel 136 on the end of the combined arm 133, 134 and the end is then tied onto any convenient part of the machine. As the shaft 105 is oscillated, and referring to Fig. 1, the path of movement of the lacing 64 will be indicated by the dotted arrowed line thereon, the lacing, as it passes over the members 189 being guided downwardly into the angular space between cooperating pins 61 and extensions 63 and it will be noted that, under these circumstances, each reach of the lacing 64 is engaged by the feed chains 59. As they are fed forwardly, the lacings 64 have a certain portion of their length saturated with compound brought up from the tank 83 by the members 95 and 97 and then pass onwardly through the oven 185 where they are maintained in heated condition and, as they move onward and over the sprockets 58 on the shaft 57, the constantly rotating turret plate 26 brings the die structures into position to cause the saturated portion of the lacing lengths to be engaged by the die plates 31. As the die structures move in a rotary path, the cam 54 moves the die 41 into engagement with the die plate 31, the cutter 43 simultaneously cutting out a section of the lacing as the dies and die plates compress the molded or moldable material about the now tipped ends of the lacing and, as above described, the lacings are removed from the dies and counted in bundles of one gross.

When operating on extremely long lacings, the member 186 on the arm 181 is moved into the position indicated in Fig. 3 and the path of the lacing under these conditions is indicated in the full lines in Fig. 1 and it will be noted that now but one reach of the lacing 64 of indeterminate length is placed in the V space between the pin 61 and the extension 63 of the feed chains 59. Under these conditions, it is necessary, as above described, to skip one stroke of the ratchet of the pawl counting mechanism and the manner in which this is done has been clearly set forth above.

While I have necessarily shown and described the preferred embodiment of my invention somewhat in detail, it is to be understood that I may vary the size, shape, and arrangement of parts comprising my invention within wide limits without departing from the spirit of the invention.

Having thus described my invention, what I claim as new is:

1. An improved lace tipping machine comprising lace feeding means, a plurality of tipping dies, and means for bringing such dies successively into operative relation with the lace feeding means.

2. In a lace tipping machine, the combination of lacing feeding means, a rotatable

plate, a plurality of tipping dies radially disposed on said plate, and means for rotating said plate to bring said dies successively into operative relation with the lacing feeding means.

3. In a lace tipping machine, the combination of lacing feeding means, means for moving said lacing feeding means intermittently, a rotatably mounted plate, a plurality of tipping dies radially mounted on said plate, and means for rotating said plate in synchronism with the intermittent movement of the lacing feeding means to bring said tipping dies successively into operative relation with the lacing feeding means.

4. In a lace tipping machine, the combination of lacing feeding means, means for feeding lacing thereto, a tipping die movable transversely of the path of movement of the lacing feeding means for transferring a length of lacing from the feeding means to the die, and means for operating the feeding means and the die in synchronism.

5. In a lace tipping machine, the combination of lacing feeding means, an oscillating arm for feeding a succession of loops of predetermined length from a lacing of indeterminate length to the lace feeding means, a rotatable multiple die holder mounted at the exit end of the feeding means, a plurality of tipping dies radially mounted on said holder, means for bringing the plurality of dies successively into operative relation with the lacing feeding means and at the exit end thereof, means on said die for clamping a length of lacing in operative relation to the die elements, and means for operating the die to complete the tipping operation during the rotative movement of the die carrying means.

6. An improved lace tipping machine comprising lacing feeding means, means for moving said lacing feeding means intermittently, means for feeding loops of lacings of predetermined length from a lacing of indeterminate length to said lacing feeding means, during the intermittent operation thereof, a rotatably mounted die holder located at the exit end of said lacing feeding means, a plurality of tipping dies radially mounted on one face thereof, means for gripping a length of lacing and holding the same in operative relation on the die, and means associated with said dies for operating the die elements to complete the tipping operation during the rotation of the die holder.

7. In a lace tipping machine, the combination of lacing feeding means for feeding a plurality of loops of lacings of predetermined length, a plurality of tipping dies operably associated with said lacing feeding means and at the exit end thereof, means for bringing said dies successively into operative relation with the lacing feeding means,

- means for operating said dies to place a tip on each loop of lacing, and means for automatically counting the number of lacings operated on by the dies.
- 5 8. In a lace tipping machine, the combination of lacing feeding means, means for moving said lacing feeding means forwardly step by step, an oscillating arm for delivering loops of lacings of predetermined length
- 10 to the feeding means from a lacing of indeterminate length, a plurality of tipping dies associated with said feeding means, means for bringing said dies successively into operative relation with the feeding means, means
- 15 for operating said dies to place a molded or moldable tip on the loops of lacings, means associated with said dies for severing the lacings at a point intermediate the length of molded or moldable material placed
- 20 thereon, means for positively removing the lacings from the dies, and means for automatically counting the lacings delivered from the dies.
9. In a lacing tipping machine, the combination of lacing feeding means, a source of lacing supply, an oscillating feeding arm interposed between the lacing feeding means and the source of supply for delivering loops of lacings of predetermined length
- 25 from the source of supply to the lacing feeding means, and means interposed between the oscillating arm and the source of supply for severing the lacing adjacent the source of supply to prevent feeding of imperfect
- 30 lacings material to the feeding means.
10. In a lace tipping machine, the combination of lacing feeding means, means for delivering loops of lacing of predetermined length to said feeding means, means for applying molded or moldable material to a portion of each loop, means for retaining the molded or moldable material at a predetermined temperature during the feeding movement thereof, by the feeding means,
- 40 45 a plurality of dies associated with the feeding means and at the delivery end thereof, and means for feeding said dies successively across the delivery end of the feeding means.
- 50 11. In a lace tipping machine, the combination of lacing feeding means, means for delivering loops of lacing of predetermined lengths to said feeding means, means for applying molded or moldable material to a portion of each loop, means for retaining the molded or moldable material at a predetermined temperature during the feeding movement thereof by the feeding means, a plurality of dies, and means for moving
- 55 60 65 said dies, in succession, across the path of movement of the feeding means and at the delivery end thereof to engage with the molded or moldable portion of the lacing to the die in predetermined position with relation thereto,
12. In a lacing tipping machine, the combination of step by step feeding means, a plurality of tipping dies associated therewith and at the exit end thereof, means for bringing said dies successively into operation with the exit end of the lacing feeding means, and means for operating the feeding means in synchronism with the movement of the dies.
13. In a lace tipping machine, the combination of lacing feeding means comprising a plurality of articulated links, means associated with each link for gripping a lacing, means operable in synchronism with the speed of the movement of the feeding chains for feeding a length of lacing to each link, a multiple die holder, a plurality of tipping dies thereon, and means for rotating the multiple die holder to bring a die into position with each link of the feed chain.
14. In a lace tipping machine, the combination of a lacing feeding means comprising a plurality of articulated links, means for feeding a loop of lacing to each alternate link, a tipping die, and means for bringing such die into operative relation with each alternate link of the feed chain.
15. In a lace tipping machine, the combination of a feeding mechanism, means for moving said feeding mechanism step by step in a horizontal plane, a rotatable die holder, a plurality of tipping dies thereon, means for rotating said die holder in a vertical plane at a predetermined speed with relation to the rectilinear speed of the feeding mechanism, and means for alternating the relative speed of the feeding mechanism and die holder at will.
16. A lace tipping machine, including a plurality of dies, means for bringing said dies successively into operation, and means for operating said dies.
17. A lace tipping machine, including a plurality of tipping dies, means for actuating said dies successively on laces, and means for maintaining each of said dies in lace tip engaging position for a predetermined time.
18. A lace tipping machine, including a plurality of tipping dies, means for actuating said dies successively on laces, and means for maintaining a die operative while a succeeding die is inoperative.
19. A lace tipping machine, including a plurality of tipping dies, means for actuating said dies successively on laces, and means for maintaining a plurality of dies operative while a plurality of succeeding or preceding dies are inoperative.
20. In a lace tipping machine, lace feeding means, a plurality of lace feeding instrumentalities cooperating with said feeding means, constructed and arranged for certain of said dies to maintain tip forming pressure during a predetermined time.

21. A lace tipping machine comprising a movable carrier, tipping devices on said carrier, and means to operate the same.

22. A lace tipping machine comprising a movable carrier, a plurality of sets of tipping devices on said carrier, and means to operate the same.

23. In a lace tipping machine, a carrier operable in a cycle of movements, tipping devices on said carrier, and means for maintaining said devices in operative and inoperative positions at predetermined intervals during said cycle of movements.

24. In a lace tipping machine, a carrier operable in a cycle of movements, a plurality of sets of tipping devices on said carrier, and means for maintaining said sets of devices in operative and inoperative posi-

tions at predetermined intervals during said cycle of movements.

25. In a lace tipping machine, a rotatable die carrier, means to operate on lace tips secured to said carrier, and mechanism to render the same operable and inoperable at predetermined intervals during the rotation of said carrier.

26. In a lace tipping machine, a plurality of rotatable die carriers, means to operate on lace tips secured to said carriers, and mechanism to render the same operable and inoperable at predetermined intervals during the rotation of said carrier.

In testimony whereof, I have signed my name to this specification.

CARL A. MATSON.
